UNITED STATES PATENT OFFICE.

EDWARD N. MAULL, OF CRESCENT CITY, FLORIDA.

BINDER FOR CRATES, BOXES, &c.

No. 800,228.

Specification of Letters Patent.

Patented Sept. 26, 1905.

Application filed February 29, 1904. Serial No. 195,927.

To all whom it may concern:

Be it known that I, EDWARD N. MAULL, a citizen of the United States, residing at Crescent City, in the county of Putnam and State 5 of Florida, have invented a new and useful Binder for Crates, Boxes, and the Like, of which the following is a specification.

This invention relates to the flexible binders employed upon crates, boxes, and similar 10 closures, and has for its object to provide a flexible binder having slidably disposed thereon flexible plates bendable with the binder over the corners of crates, boxes, and the like to form a corner-guard to the same and to 15 protect the binder.

With these and other objects in view, which will appear as the nature of the invention is better understood, the same consists in certain 20 novel features of construction, as hereinafter fully described and claimed.

In the accompanying drawings, forming a part of this specification, and in which corresponding parts are denoted by like designating characters, is illustrated the preferred form 25 of the embodiment of the invention capable of carrying the same into practical operation, it being understood that the invention is not necessarily limited thereto, as various changes in the shape, proportions, and general assem- 30 blage of the parts may be resorted to without departing from the principle of the invention or sacrificing any of its advantages, and the right is therefore reserved of making all the changes and modifications which fairly fall 35 within the scope of the invention and the claims made therefor.

In the drawings thus employed, Figure 1 is a perspective view of a portion of one of the improved binders as furnished for application 40 to crates, boxes, and the like. Fig. 2 is a perspective view, enlarged, of one of the slidable attachments. Fig. 3 is an end view of a crate with the improved binder applied. Fig. 4 is a view of portions of the abutting ends of the binder with one of the improved attachments applied as a guard thereto. Fig. 5 is an enlarged view of one of the binders at one of its 45 "bends."

The binders employed upon crates, boxes, 50 and similar closures are generally of flexible wood, bent around the corners and nailed to the crate or box, and in thus bending the wood it is liable to partial fracture and cause a weakening of the binder at the corners of the crate. 55 The partial fracture of the binder also produces rough and jagged splinters, which pre-

sent an unsightly appearance, besides catching upon surrounding objects or the clothing of persons passing by and often resulting in tearing the binder loose from the crate or box. 60 To avoid these objections is the principal object of the present invention, which consists, primarily, of a flexible binder member 10, having slidably disposed thereon flexible plates 11, preferably of metal, and mounted slidably 65 upon the binder, so that they can be adjusted opposite the points where the binder is to be bent and then bent with the latter over the corners of the crates, boxes, and the like (shown at 12) and not only form a guard to 70 prevent the splinters caused by the partial fracture of the binder at the bends from protruding, but also frequently entirely preventing the fracture of the binder. The plate also forms a corner-guard to the crate or box, 75 which not only protects the same, but materially increases its strength and comeliness of appearance.

Means will be employed for mounting the plates 11 slidably upon the binder 10, so that 80 they can be adjusted longitudinally thereof to adapt the binder for application to different sizes and forms of crates, boxes, and similar closures.

Binders of any length, together with a supply of the plates either separately or "threaded" upon the binders, may be furnished to shippers and others requiring them and readily applied, the plates being adjusted longitudinally to correspond to the sizes or forms 90 of the closures and the surplus material, if any occurs, cut off. By this means binders may be constructed long enough for the largest crate or box and quickly applied thereto or as quickly applied to the smaller sizes by cutting off the surplus material, the slidable plates being readily adjustable to all sizes and forms of closures, as will be obvious.

An approved means is shown for slidably mounting the plates upon the binders, consisting in lateral projections 13 at the ends of the plates for bending beneath the same with their free ends interfolded, as at 14, and forming loops or guideways for slidably engaging the binder, as will be obvious. By this simple arrangement a very convenient, practical, and efficient device is produced by which the strength of the binder is materially increased and at small expense and the crate or box firmly supported and protected at the corners 110 and the adjacent ends of the binder likewise protected and guarded.

Nail-holes 16 will preferably be formed through the binder members 10 at suitable intervals, and nail-holes 15 will also be formed through the plates 11 to receive the securing-nails and obviate any liability of the splitting of the binder by careless nail-driving by the packers.

The binder members may be of any required size or length and of any suitable material, but will generally be of the size and material usually employed for this purpose.

The improved binder will be especially applicable to securing the crates, cases, or boxes containing fruit, but may be employed for any form or size of such closures or to closures employed for any purpose.

Having thus described my invention, what I claim is—

1. As an article of manufacture, a binder for crates and the like, comprising a bendable strip and a guard member slidably embracing the strip and capable of being set to any point thereon and of bending therewith to protect the strip at a bend therein.
2. As an article of manufacture, a binder for crates and the like, comprising a bendable strip, and a guard member slidably embracing the same and capable of being set to any point thereon and of bending with the strip to pro-

tect the same at a bend therein, the guard being provided with a perforation for the reception of a fastening to fix the same upon the strip.

3. As an article of manufacture, a binder for crates and the like, comprising a bendable strip and a guard member in the form of a plate provided at opposite ends with loops slidably embracing the strip, said guard capable of being moved to any position upon the strip and bendable with the latter to protect the same at a bend therein.

4. As an article of manufacture, a guard for binder-strips comprising a bendable plate provided at opposite ends with transversely-disposed alined loops for the reception of a binder-strip.

5. As an article of manufacture, a guard for binder-strips comprising a bendable plate provided at each end with opposite lateral extensions which are bent to form a loop with the ends of the extensions interfolded.

In testimony that I claim the foregoing as my own I have hereto affixed my signature in the presence of two witnesses.

EDWARD N. MAULL.
